ADJUSTABLE MOUNTING FOR FASTENERS

Adolph Ostwald, New York, N. Y.

Application April 22, 1939, Serial No. 269,509

14 Claims. (Cl. 2—265)

This application is a continuation-in-part of the pending application, Serial No. 133,757, filed March 30, 1937.

The primary object of the invention is to provide readily adjustable garments, particularly uniforms.

It is also proposed herein to provide an adjustable mounting for fastening means so that a garment may be varied in size according to the selected location of the mounting and fastening means.

Garments of the type contemplated have long been needed, not only for military purposes, but also in schools and bands where there is an annual turnover in personnel, and where also the uniforms must be adjusted from time to time to fit the individual owners.

Since, in adjusting the size of a garment comparatively long seams must be "let out" or "taken in," as the case may be, it is intended to provide a mounting that is flexible along its length.

Another object is to provide an adjustable mounting which will not slip, cannot accidentally be torn loose from a garment, and which will not tear, pull, stretch, or distort the material in which it is attached.

Moreover, it is further intended to provide a device for attaching two or more pieces of material together. At the same time, a part of the invention lies in the provision of a simple tool which may be a part of the main structure in one instance, or which may be used separately to facilitate attaching the mounting on the garment or on the materials joined.

Still again, it is intended to provide a device which will cause no physical discomfort, which will not be exposed to view, and will thus, when used in an adjustable uniform as proposed, not mar the appearance in any way.

Other objectives of the invention, such as ease in manufacture, assembly and mounting, durability, and simplicity will be found present in the following specification and drawings in which:

Fig. 1 is a back elevation of a uniform with a portion turned back to show part of the mounting;

Fig. 2 is a back elevation similar to Fig. 1, but showing the uniform as seen in ordinary use;

Fig. 3 is a plan view of one portion of the insert in one form of the device;

Fig. 4 is a plan view of the receptor;

Fig. 5 is a plan view showing the receptor in dotted lines below a sheet of material at the com-

pletion of the first step in attaching the mounting;

Fig. 6 is a view similar to Fig. 5, but with the mounting completely attached;

Fig. 7 is a section along lines 7—7 of Fig. 5;

Fig. 8 is a section along lines 8—8 of Fig. 6;

Fig. 9 is a transverse section through a garment as shown in Fig. 2, but with the front closed;

Fig. 10 shows an insert according to another form of the invention;

Fig. 11 is an enlarged view similar to Fig. 4, but partially broken away;

Fig. 12 is a plan view showing one step in the use of the device shown in Figs. 10 and 11;

Fig. 13 is a section along the lines 13—13 of Fig. 12;

Fig. 14 is a view similar to Fig. 12, but showing a later step;

Fig. 15 is a section along lines 15—15 in Fig. 14, and

Fig. 16 shows the tool accessory.

Referring to the form shown in Figs. 1 to 9, inclusive, the reference numeral 2 indicates a uniform having an adjustable collar 3 and sleeves

25 4. To the material 5 along one side of the back opening a slide-fastener element 6, having a connector 7 at its top and slide fastener 8 is secured. The tape 9 is permanently secured by stitches 10 to the inside of the material 5 and set back from the edge thereof so that the material 5 overlaps the fastener element 6, as shown particularly in Figs. 1, 2 and 9.

On the other side of the back opening, herein-after called the adjustment side 12, a complementary slide fastener 14, having a connector 15 complementary to the connector 7 is adjustably mounted.

The adjustable mounting of the slide fastener element 14 is accomplished by the receptor element 16, shown best in Figs. 4 and 11, which consists of a series of C-shaped members 18, which may be of metal, plastic, molded composition, or other material, each having opposed jaws 19 which form the mouth openings 20. The C-shaped members 18 are held together in end-to-end relationship by means of flexible cat gut strings 21, which are passed in and out of the holes 22 as shown in Fig. 11, and thus provide

30 35 40 45 50 the semi-continuous channel 24 running from end to end in the flexible receptor element 16.

Fig. 3 shows the insert 25 which includes the tape 26, on one edge of which is attached the slide fastener element 14. On the other edge of tape 26 are beads 28, which are smaller than

the width and depth dimensions of channel 24 within the C-shaped members. As shown in Figs. 3, 8 and 9, the beads 28 are strung on the flexible cat gut string 29, attached to the tape 25 by stitches 28a.

On one end of the insert 25 is the stop member 30 and the metal plate 31. The metal plate is attached to the tape by a rivet 33 for supporting the connector 15 to facilitate engagement of connectors 7 and 15 preliminary to operating the slide fastener 8. On the other end is the pull tab 32. As shown in Figs. 3, 5 and 6, the pull tab 32 has an eyelet 34 at one end, the string 29 being fastened through the eyelet. The portion around the eyelet is also smaller than the channel 24, and the neck 36 on the tab is smaller than the mouths 19 in the C-shaped members. The broad end of the pull tab forms a spade portion 38, which is offset as shown in Fig. 5.

The uniform is exceedingly easy to fit or adjust to any desired size. The final location of the slide fastener 14 with respect to the edge of the material on the adjustment side 12 is first determined by fitting the coat 2 to the wearer. Then, after marking the material, first allowing for the width of the tape 25, the receptor element is placed on any convenient flat surface, with the mouths 20 of the C-shaped members 18 facing upwardly. The marked portion of the material 12 is placed over the receptor element 16, with the front facing upwardly, the spade portion 38 of the pull tab is used to push the material 12 down through the mouths 20 and into the channel 24 by running it along the top of the material as shown in Fig. 7. Figs. 5 and 7 show the assembly at the end of this stage.

Next, the eyelet end of the pull tab is placed in the end of the channel 20a which has now been formed in the material 12, and the beads 28 are pulled into the channel 20a to the position in Figs. 6 and 8. The coat may then be fastened in the usual manner by engaging the connectors 7 and 15 and operating the slide fastener 8, as shown in Fig. 9.

A form of the invention particularly suitable for joining two or more pieces of cloth, such as at the back seam of a uniform, or in any other structure where an overlap between the materials to be joined is obtainable, is shown in Figs. 10 to 16, inclusive.

In the latter figures, a beaded insert chain 40 (see Fig. 10), comprising elongated beads 42 strung on the flexible string 44 is used in conjunction with the receptor element 16, shown in Figs. 4 and 11.

Two layers of cloth, the upper 46, and the lower 48, are placed together with their common edges adjacent. The receptor element 16 is placed beneath the layers, set in from the edges, and the end of the beaded chain 40 is placed near one end of the receptor.

In place of the pull tab 32, an inserter 50 having a slot 52, a neck 54, handle portion 56, and the depressor 58 is used as follows. The slotted end of the inserter is engaged with the chain 40 as shown in Fig. 16. The depressor is used to force the cloth into the channel 24 in the receptor by running it along the cloth over the mouths 20 and thus provides the channel 20a'. At the same time the slotted end of the inserter is started in the end of the channel 20a, and the chain 40 is pulled into the channel 20a' behind the depressor to the position shown in Figs. 12 and 13.

Instead of the inserter shown in Figs. 16, a small roller may be used to force the chain 40 into the channel 20a through the partially closed mouth thereof.

5 Finally, the upper layer 46 is folded over as shown in Figs. 14 and 15.

As will be seen in each case, it is impossible for the beaded element to be dislodged accidentally from the receptor element because of the reverse pull on the two layers of cloth. In some cases, where the inserter 50 is used, the beads are larger than the mouths 20 which have been partially closed by the material.

15 In the foregoing specification there has been described an adjustable uniform which, while capable of being fitted to many different sized wearers in succession, does not bear the stigma of a "hand-me-down" because the features which provide adjustments are not visible.

15 In the adjustable mounting for the separable fastener, qualities of flexibility, ruggedness, simplicity, and economy are combined to achieve comfort, confidence, operability, and availability in and to the user.

The adaptations of the invention are suitable for joining any flexible sheet materials, not only in uniforms and other garments, but also in tents, covers, bags, and the like.

30 The invention thus described is not limited to the specific disclosure, but only by the compass of the following claims.

I claim:

1. An adjustable fastener for joining flexible sheet materials comprising an elongated, non-rigid receptor, said receptor having a partially closed mouth channel, with at least one open end, extending along the length thereof, said receptor being formed of a plurality of rigid elements defining said channel and said mouth and articulating means supporting said elements in series, and a non-rigid insert engageable within said channel, said insert being adapted and arranged, with respect to the first-named means, to be slid into said channel only from the open end thereof.

45 2. An adjustable fastener for joining flexible sheet materials, comprising an elongated, non-rigid receptor having a partially closed mouth channel, with at least one open end, extending 50 along the length thereof for holding an open crease of said material therein, said receptor being formed of a plurality of rigid elements defining said channel and said mouth and articulating means supporting said elements in series, and an elongated, non-rigid insert engageable 55 within said crease.

60 3. In combination with an adjustable fastener as claimed in claim 2, an inserting tool having a portion engageable with said insert, said portion being engageable within said channel, but larger 65 than the open mouth thereof, a neck portion smaller than said open mouth, and a depressor portion for creasing said material into said channel.

65 4. An adjustable fastener as claimed in claim 2, said insert comprising a string of beads.

70 5. An adjustable mounting for a separable fastener element comprising an elongated, non-rigid receptor, said receptor having a partially closed mouth channel, with at least one open end, extending along the length thereof, said receptor being formed of a plurality of rigid elements defining said channel and said mouth and articulating means supporting said elements in series, 75 a non-rigid insert engageable within said chan-

hel, said insert being adapted and arranged, with respect to the first-mentioned means, to be slid into said channel only from the open end thereof, said element being secured to said insert.

6. An adjustable mounting for attaching a separable fastener element to a sheet of flexible material, comprising an elongated, non-rigid receptor, said receptor having a partially closed mouth channel, with at least one open end, extending along the length thereof for holding a crease of said material therein, means defining said channel and said mouth, and an elongated, non-rigid insert engageable within said crease, said means comprising a plurality of rigid elements spaced along non-rigid supporting means, said insert including a plurality of rigid elements and articulating means supporting said elements in series and being adapted and arranged with respect to the first-mentioned means to be slid into said crease only from the open end of said channel, said separable fastener element being secured to said insert.

7. An adjustable mounting as claimed in claim 6, said insert having a pull tab secured at one end thereof, said pull tab having an eyelet portion engaged with said insert, said eyelet portion being slideable along said fold, a neck portion smaller than said mouth, and a handle, said handle being substantially flat for pressing said material into said channel whereby to form said fold.

8. An adjustable mounting for attaching a separable fastener element on a sheet of flexible material, comprising an elongated, non-rigid receptor, said receptor comprising a plurality of C-shaped members spaced from one another, and held in end-to-end relationship, flexible means for attaching said members together whereby to form a partially closed mouth channel extending along the length thereof for holding a crease of said material therein, and a non-rigid insert engageable in said crease within said channel from the end thereof, the thickness of said receptor element being substantially equal to the width of said mouth, said fastener element being attached to said insert.

9. An adjustable mounting for attaching a separable fastener element on a sheet of flexible material, comprising an elongated, non-rigid receptor, said receptor comprising a plurality of C-shaped members slightly spaced from one another and held in end-to-end relationship by means of flexible cat gut laced through holes in the side walls of said members, respectively, thus to provide a partially closed-mouth intermittent channel extending lengthwise of said receptor for holding a crease of material therein, an elongated, non-rigid insert comprising a plurality of beads mounted in spaced relation to one another along one edge of a strip of flexible material, said fastener element being mounted along the other edge of said strip, said beads being relatively smaller than said channel, but substantially equal, in size, to the width of the mouth of said channel whereby, when said in-

sert is slid into said fold from the end of said channel, the material forming the fold and said beads will prevent the withdrawal of either through the mouth of the channel.

10. An adjustable mounting as claimed in claim 9, a pull tab attached to one end of said insert adjacent the beaded edge thereof, said pull tab having an eyelet portion engaged with said insert, said eyelet portion being smaller in all dimensions than said channel, a neck portion smaller in all dimensions than the mouth of said channel, and a substantially flat handle portion for creasing said flexible material into said channel.

11. An adjustable fastener for joining flexible sheet materials, comprising an elongated, non-rigid receptor, said receptor comprising a plurality of substantially C-shaped members slightly spaced from one another and held in end-to-end relationship by means of flexible cat gut laced through holes in the walls of said members, respectively, thus to provide a partially closed mouth intermittent channel extending lengthwise of said receptor for holding creases of said materials extending therein, and non-rigid string of elongated beads insertable into said folds.

12. In combination with an adjustable fastener as claimed in claim 11, an inserter, said inserter comprising a slotted portion engageable with the string of said beads, said slotted portion being slideable into said channel and the creases of material therein from the end, a neck portion smaller than the mouth of said channel, a bent handle, and an element extending downwardly from said handle for depressing said flexible material into said channel as said member is moved therealong to insert said string of beads.

13. An adjustable fastener for joining flexible sheet materials, comprising an elongated, non-rigid receptor having a partially closed mouth channel extending along the length thereof, said receptor being formed of a plurality of elements substantially C-shaped in cross section and being joined by a pair of flexible string-like members, said members being secured, respectively, to the opposed sides of said elements, and an elongated, non-rigid insert engageable within said channel for holding said flexible sheet materials therein.

14. An adjustable fastener for joining flexible sheet materials, comprising an elongated, non-rigid receptor having a partially closed mouth channel extending along the length thereof, said receptor being formed of a plurality of rigid elements substantially C-shaped in cross section and being joined by a pair of flexible string-like members, said members being secured, respectively, to the opposed sides of said elements, and an elongated, non-rigid insert engageable within said channel for holding said flexible sheet materials therein.

ADOLPH OSTWALD.
